UNITED STATES PATENT OFFICE.

ARTHUR H. WOLFE, OF PHILADELPHIA, PENNSYLVANIA, ASSIGNOR OF ONE-HALF TO
DURWARD A. WOLFE, OF GRAND RAPIDS, MICHIGAN.

COLLAPSIBLE CASE.

Application filed October 16, 1924. Serial No. 744,011.

To all whom it may concern:

Be it known that I, ARTHUR H. WOLFE, a citizen of the United States, residing at Philadelphia, in the county of Philadelphia and State of Pennsylvania, have invented certain new and useful Improvements in Collapsible Cases; and I do declare the following to be a full, clear, and exact description of the invention, such as will enable others skilled in the art to which it appertains to make and use the same.

My invention relates to improvements in foldable cases for containing numerous articles, such as cigarettes, matches, playing cards, visiting cards, stamps, and a myriad of others, one object of the present invention being to provide an advantageous variation over the construction shown in my pending U. S. application, Serial No. 725,274, permitting the article container and the sheath in which it is movably mounted to be inverted in the outside casing.

Another object of the invention is to provide a construction in which the article container is moved out of the sheath, when said container and sheath are inverted with respect to the outside casing, giving easy access to the contents of said container.

A further object is to provide an outside casing of novel construction to permit any movable member which may be mounted in it, to be moved to either of two relatively inverted positions, thus adapting the casing not only for holding numerous forms of article containers, but possibly for holding complete articles, for instance, mirrors, brushes and numerous other toilet articles.

With the foregoing in view, the invention resides in the novel subject matter hereinafter described and claimed, the description being supplemented by the accompanying drawing.

Figure 1 is a perspective view of one form of the case in its completely closed position.

Figure 2 is a perspective view partly in section showing the sheath and the article container therein, swung upwardly preparatory to inverting them.

Figure 3 is a perspective view showing one form of the outside casing.

Figure 4 is a perspective view showing one of the many article containers which may be mounted in the sheath which is in turn

mounted slidably and pivotally in the outside casing.

Figure 5 is a perspective view of the sheath.

Figure 6 is a longitudinal sectional view showing the sheath and the article container inverted within the outside casing and the container held in an inclined position.

Figure 7 is a vertical sectional view on line 7—7 of Fig. 2.

Figures 8 and 9 are perspective views showing different constructions for the outside casing.

I will first describe the form of construction illustrated in Figs. 1 to 7, which construction comprises briefly an outer substantially flat casing 1 having an open side, a sheath 2 normally confined within the casing and also having at least one open side, and an article container 3 within the sheath capable of outward movement through the open side thereof when said sheath and container are swung outwardly from the outside casing as seen in Fig. 2, the construction being also such that the sheath and the article container may be entirely inverted 80 and the former re-inserted in the outside casing.

The casing 1, in the construction under consideration, comprises a flat bottom plate 4, a front wall 5 rising therefrom, a back wall 6, and a pair of opposed side walls 7. The bottom plate 4 and all of the walls 5, 6 and 7 are preferably formed from a single piece of sheet metal, such as aluminum, and when the walls 7 are stamped, they are formed about twice as wide as the front and back walls 5 and 6, so that said walls may have their upper portions bent inwardly and downwardly to provide flat vertical flanges 8 at the inner sides of the side walls proper, the latter being preferably bowed outwardly away from the flanges as seen for instance in Figs. 2, 3 and 7. The front and back walls 5 and 6 are also by preference curved transversely as shown, so that a rounded formation is provided at all edges of the casing, giving an attractive appearance and overcoming danger of any sharp edges injuring the lining of the user's pocket in which the article may well be carried.

The flanges 8 are formed with longitudinal slots 9 extend from end to end thereof and constituting tracks for a purpose to appear,

entrance throats 10 being formed into the slots 9, the function of these throats being also described hereinafter.

The sheath 2 may be of any suitable form, but it is preferably of the general U-shape shown, being provided with two parallel flat side plates 11 and with a transversely curved front wall 12. This sheath is also preferably provided with a flat side wall 13 adjoined to the plates 11 and wall 12, said side wall 13 however having a large opening 14 for a purpose to appear, while the side plates 11 are preferably formed with arcuate slots 15 whose function will also be set forth later.

The article container 3 is received within the sheath 2 and it may be of any desired construction. As the construction herein disclosed is similar to that shown in my U. S. application Ser. No. 725,274, such construction will not be specifically described. It may be stated however that this container has each of its end walls provided with an opening 16 adjacent its lower end, the openings being in alinement and adapted to register with openings 11' in the end plates 11 of the sheath. A rod 17 passes through the registering openings 16 and 11' of the container walls and free ends of the plates 11, and the ends of this rod project slightly beyond the side plates and are provided with any appropriate flat heads 18. The projecting portions of the rod 17 and the heads 18 are downwardly insertible through the throats 10 of the casing 1, so that said portions of the rod will be received in the slots or tracks 9 and will constitute shoes which may slide along said tracks from one end to the other thereof. The wall 12 of the sheath 2 is provided with a knob 19 having a shank 20 receivable in either of a pair of slots 21 formed in the free edges of the front and back walls 5 and 6, according to the position of the sheath and container in the outside casing. It will be seen that by pushing upwardly upon this knob, the sheath and container may be swung upwardly out of the casing, the rod 17 then forming a pivot. When this pivotal action takes place, the rod is at one end or the other of the tracks 9, but after such swinging has been accomplished, the rod may be slid entirely to the other end of the tracks, so that the sheath 2 and the article container 3 may be inverted in the outside casing 1.

The article container 3 is provided with oppositely projecting lugs 22 which pass through the arcuate slots 15 of the sheath 2 and project slightly beyond the side walls 11 of said sheath. When the sheath and container are closed into the casing 1, these lugs are received in notches 22^a in the side walls 7 of said casing, as shown in Fig. 1, permitting the sheath 2 to fold completely into said casing and lie flush with the edges

of its walls. When the sheath and container however are swung upwardly to the position of Fig. 2, slid toward the opposite end of the casing 1, and then moved downwardly so that the sheath is received in said casing, the lugs 22 are receivable in notches 22^b in the upper edges of the side walls 7, so that while the sheath is permitted to move entirely into the casing, the article container 3 is moved out of said sheath and is held in the inclined position shown in Fig. 6 so that its contents are readily accessible. If it is desired to outwardly swing the container from the sheath when the parts are in substantially the position of Fig. 2, it will be seen that the user's fingers may be passed through the opening 14 and pressed against said container to swing it outwardly in the desired manner.

In Fig. 8, a casing structure is shown which differs from that previously described, in that only the intermediate longitudinal portions of the side walls 7^a are transversely bulged as indicated at 43. These walls are provided with downwardly projecting flanges 8^a and with slots 9^a which extend from end to end of said flanges.

A still further simplified casing structure is shown in Fig. 9, in which the opposed side walls 7^b of the casing are of one ply construction and are strictly flat, track forming slots 9^b being formed through said walls one end thereof to the other.

Any desired invertible member or members may be used in the improved casing structure and wherever the sheath 2 is employed, it will be further understood that any desired article or articles may be mounted in this sheath. It will be further understood that the invention is not restricted to any particular field of use and the details of construction may vary as occasion may demand.

I claim:

1. A device of the class described comprising a casing having an open upper side, said casing being provided with tracks throughout the length of two of its opposed side walls, a sheath within the casing having an open side normally disposed downwardly, said sheath having shoes engaging the aforesaid tracks and mounting the sheath pivotally and slidably in the casing, so that it may be moved out of said casing, inverted and reinserted into the casing in an inverted condition, a member movably mounted in said sheath, and means for projecting said movable member from the open side of said sheath when the latter is inverted and reinserted into the casing.

2. A device of the class described comprising a casing having an open upper side, said casing being provided with tracks throughout the length of two of its opposed side walls, a sheath within the casing hav-

ing an open side normally disposed downwardly, said sheath having shoes engaging the aforesaid tracks and mounting the sheath pivotally and slidably in the casing, so that it may be moved out of said casing, inverted and reinserted into the casing in an inverted condition, a movable member in said sheath having projections extending beyond said sheath, said projections being adapted to strike parts of the casing and project said movable member from the open side of said sheath when the latter is inverted and reinserted into the casing.

3. A device of the class described comprising a casing having an open upper side, said casing being provided with tracks throughout the length of two of its opposed side walls, a sheath within the casing hav-

ing an open side normally disposed downwardly, said sheath having shoes engaging the aforesaid tracks and mounting the sheath pivotally and slidably in the casing, so that it may be moved out of said casing, inverted and reinserted into the casing in an inverted condition, a movable member pivotally mounted in said sheath, and a lateral projection carried by said member and extending beyond one wall of the sheath, said projection being adapted to strike a side wall of the casing and project the movable member from the open side of the sheath, when the latter is inverted and reinserted into the casing.

In testimony whereof I have hereunto affixed my signature.

ARTHUR H. WOLFE.
